Filed Apr. 2, 1974, Ser. No. 457,361

Term of patent 14 years

Int. Cl. D23—03

U.S. Cl. D23—97

FIG. 1 is a perspective view of a freestanding fireplace showing my new design;

FIG. 2 is a rear elevational view thereof;

FIG. 3 is a front elevational view thereof;

FIG. 4 is a left side elevational view thereof;

FIG. 5 is a top plan view thereof;

FIG. 6 is a bottom plan view thereof;

FIG. 7 is a front elevational view of a modified form of my new design;

FIG. 8 is a side elevational view thereof;

FIG. 9 is a rear elevational view thereof;

FIG. 10 is a top plan view thereof;

FIG. 11 is a bottom plan view thereof;

FIG. 12 is a front elevational view of another modified form of my new design;

FIG. 13 is a left side elevational view thereof;

FIG. 14 is a rear elevational view thereof;

FIG. 15 is a top plan view thereof;

FIG. 16 is a bottom plan view thereof;

FIG. 17 is a front elevational view of yet another modified form of my new design;

FIG. 18 is a side elevational view thereof;

FIG. 19 is a rear elevational view thereof;

FIG. 20 is a top plan view thereof; and

FIG. 21 is a bottom plan view thereof.

The invention is characterized generally by a thick-walled truncated-pyramid shape having an inner truncated pyramid visible at the top.

I claim:

The ornamental design for a freestanding fireplace, as shown and described.
